Attorney

UNITED STATES PATENT OFFICE.

EDWARD R. DROHAN, OF LYNN, MASSACHUSETTS.

UMBRELLA.

1,107,415.

Specification of Letters Patent. Patented Aug. 18, 1914.

Application filed April 1, 1914. Serial No. 828,838.

To all whom it may concern:

Be it known that I, EDWARD R. DROHAN, a citizen of the United States, residing at Lynn, in the county of Essex and State of Massachusetts, have invented certain new and useful Improvements in Umbrellas, of which the following is a specification, reference being had to the accompanying drawings.

10 This invention relates to certain improvements in umbrellas and the like and has relation more particularly to a rib adapted to be employed in connection therewith; and the object of the invention is to provide 15 a device of this general character which may be applied or removed from operative position with convenience and facility.

The invention consists in the details of construction and in the combination and 20 arrangement of the several parts of my improved umbrella whereby certain important advantages are attained and the device is rendered simpler, less expensive and otherwise more convenient and advantageous for 25 use, all as will be hereinafter more fully set forth.

The novel features of the invention will be carefully defined in the appended claims.

In order that my invention may be the 30 better understood, I will now proceed to describe the same with reference to the accompanying drawings, wherein—

Figure 1 is a view in elevation and partly in section of a fragment of an umbrella structure, showing ribs and stretchers constructed in accordance with an embodiment of my invention; Fig. 2 is an enlarged fragmentary sectional view illustrating a rib, constructed in accordance with my invention, in locked position; Fig. 3 is a view, detached, of the slide employed in the present embodiment of my invention; and Fig. 4 is a view similar to Fig. 2, but illustrating the parts in open relation.

45 As disclosed in the accompanying drawings, 1 denotes a portion of a rib and 1^a a portion of a stretcher, each herein disclosed as substantially U-shape in cross section and of a conventional form. Suitably secured 50 in the upper end of such rib and the lower end of the stretcher is an engaging member 2, herein disclosed as comprising a wire strand of suitable gage having one extremity projecting beyond the adjacent end of 55 the rib 1 or stretcher 1^a to form the hook member 4 adapted to be engaged in a con-

ventional manner with either the notch or runner of an umbrella structure. The body portion of the engaging member is adapted to be secured in position in any desired manner such as by welding or solder. I do not wish to be understood as limiting myself in any way in this particular regard.

The inner extremity of the strand is flexed to afford the upwardly and outwardly directed spur member 5 of a predetermined length adapted to serve as a latch to engage the inner extremity or end of the sleeve 6 slidably mounted on the rib 1 or stretcher 1^a and maintain the same in such position relative to the hook member 4 to prevent the same from becoming disengaged from a notch or runner, as is believed to be clearly apparent to those skilled in the art to which the present invention appertains. It is thought to be obvious that should it be desired to remove a rib or stretcher for the purpose of replacement or repair, it will only be necessary to depress the spur member 5 and slide the sleeve 6 away from the hook member 4 whereupon such hook member 4 may be detached from its coacting notch or runner with convenience and facility. It is also to be observed that the inner extremity of the sleeve 6 affords a shoulder 7 with which a latch 5 engages.

In order that the coaction between the sleeve 6 and the hook member 4 may be more effective, I find it of advantage to have the outer end portion of such sleeve enlarged, as indicated at 3, so as to receive the free extremity of the hook member 4 when such sleeve is in operative adjustment.

From the foregoing description, it is thought to be obvious that an umbrella constructed in accordance with my invention is of an extremely simple and comparatively inexpensive nature and is particularly well adapted for use by reason of the convenience and facility with which it may be assembled and by reason of the effectiveness with which it performs its functions, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

In combination with a rib of an umbrella structure, a retaining member comprising a resilient metal strand having one extremity formed into a hook projecting beyond an extremity of the rib, the other extremity of said strand being bent upwardly and outwardly to afford a latch, and a sleeve slidably carried by the rib to surround the strand and close the hook extremity to com-

plete a loop, said sleeve carrying a shoulder to engage the latch to maintain the same against movement away from the hook.

In testimony whereof I hereunto affix my signature in the presence of two witnesses. 15

EDWARD R. DROHAN.

Witnesses:

SAMUEL F. BAEHELLE,
EVA M. JOHNSON.
